United States Patent Office

Des. 182,628

Patented Apr. 22, 1958

182,628

PORTABLE FLAME THROWER

Nathan F. Scudder, Santa Monica, Calif., assignor to Aerojet-General Corporation, Azusa, Calif., a corporation of Ohio

Application February 20, 1956, Serial No. 40,494

Term of patent 14 years

(Cl. D30—1)

Fig. 1

Fig. 3

Fig. 1 is a rear elevational view of a portable flame thrower showing my new design;

Fig. 2 is a side elevational view of my portable flame thrower; and

Fig. 3 is a top plan view thereof.

I claim:

The ornamental design for a portable flame thrower, as shown.
